UNITED STATES PATENT OFFICE

FLETCHER SMITH AND JOE VANE SMITH, OF MERTENS, TEXAS.

PLOW ATTACHMENT.

SPECIFICATION forming part of Letters Patent No. 773,431, dated October 25, 1904.

Application filed May 21, 1904. Serial No. 209,006. (No model.)

To all whom it may concern:

Be it known that we, FLETCHER SMITH and JOE VANE SMITH, citizens of the United States, residing at Mertens, in the county of Hill and State of Texas, have invented new and useful Improvements in Plow Attachments, of which the following is a specification.

This invention relates to plow attachments; and the principal object of the invention is to provide a simple, light, yet comparatively strong article of this character by which a walking-plow can be readily and quickly transformed into a riding or sulky plow, or vice versa.

While we do not limit the use of the attachment to any particular plows, it has been found particularly advantageous in conjunction with so-called "double-burster" plows.

In the drawings accompanying and forming a part of this specification we have represented one simple and convenient adaptation of the attachment which will be hereinafter set forth in detail; but we do not restrict ourselves to the disclosure thus made, for certain variations may be adopted within the scope of our claims.

Referring to said drawings, Figure 1 is a transverse sectional elevation of an attachment including our invention associated with a so-called "double-burster" plow. Fig. 2 is a top plan view of the attachment and plow. Fig. 3 is a sectional rear elevation of the same. Fig. 4 is a sectional side, and Fig. 5 a sectional rear, elevation of certain coupling means on an enlarged scale. Figs. 6, 7, and 8 are perspective views, also on an enlarged scale, of the three parts of the coupling means. Fig. 9 is a similar view, also on an enlarged scale, of a rack.

Like characters refer to like parts throughout the different views.

The attachment constituting the subject-matter of our invention is in the nature of a carriage, which may be rigidly connected to a plow, and such carriage involves in its construction an axle which may be of any desirable character and which axle extends when the plow is in use as a riding-plow transversely of the beam of the latter. The axle illustrated is denoted in a general way by 10 and preferably, though not necessarily, is

made of a single piece of metal. Said axle is so constructed as to allow the wheels on the same to be moved toward each other until they are a distance apart equaling that between a row or set of beds to be plowed or rebedded, as is done with double-burster plows, or away from each other until they are separated, their distance apart equaling twice the width of any row to be plowed or set of beds to be rebedded for a purpose that will be hereinafter set forth. Thus it will be seen that by our attachment we have what might be considered a single-row carriage and a double-row carriage combined in a single attachment or machine. The axle 10 is represented as arched between its ends, the arched portion being denoted by 11 and the plow-beam denoted in a general way by 12, being connected in practice directly to such arched portion. The wheels for the attachment or carriage are each denoted by 13, each wheel being adapted to be held in its adjusted position by means of collars, each denoted by 14, there being two collars in each case. These collars are held in their adjusted positions by means of set-screws adapted to engage the outer and horizontal portions of the axle, on which horizontal portions, it will be apparent, the wheels 13 can be slid toward and from each other to transform the attachment into a single-row carriage from the double-row one, and vice versa.

To the central arched portion 11 of the axle 10 we fasten in some suitable way—as, for example, by means of bolts—a frame, as 15. This frame is shown as being of yoke or of substantially inverted-V shape, the bolts, to which reference has been made, extending through the branches thereof and also through the branches or sides of the arch 11 of the axle, the frame 15 constituting a support for a segment hereinafter described.

To the axle 10, substantially centrally thereof, is detachably connected a coupling-bar, as 16. (See Fig. 7.) This coupling-bar 16 is represented as being of rectangular form in cross-section and in the present case is pivotally connected to the axle. For this purpose the lower end of the said coupling-bar 16 is forked to straddle the axle, a pivot-pin, as 17, passing through the branches of the

fork and also through a perforation in the axle. The pivot-pin 17 is shown as a screw, its forward end being tapped into the forward branch of the fork at the lower end of the bar 16, while the head of the screw is countersunk into the rear branch of said fork. Therefore it will be apparent that the bar 16 can swing about an axis extending longitudinally of the beam 12.

10 In connection with the coupling-bar 16 we provide a coupling-box, the complementary portions of which are represented best in Figs. 6 and 8 and are denoted, respectively, by 18 and 19. These box-sections 18 and 19 are of substantially similar length, and the one on the right, looking toward the front of the plow, is provided with a longitudinal groove 20 to receive the coupling-bar 16. The two sections of the box are united in any 15 suitable manner—say by bolts, screws, or the like—and each has a longitudinal slot, the slot in each case being denoted by 21. When the two sections of the box are connected together, they fit face to face, and the coupling-bar 16 will at this time lie in the groove or channel 21, from which it will be apparent that the said coupling-box can move longitudinally relatively to the coupling-bar 16.

Each section of the coupling-box has below 20 the slot therein a groove or channel 22 transverse to the slot 21 therein, which grooves register when the box-sections are united or fastened together to form a seat for the beam 12. (See, for example, Fig. 5.) It will therefore be apparent that by elevating or depressing the box the beam 12 will be correspondingly operated in order to raise or lower the point of the plow, whereby the penetration of the latter into the soil may be governed 25 by the operator. To thus raise or lower the coupling-box, we represent a hand-lever 23, (see, for example, Fig. 1,) the inner end of the hand-lever being pivoted to the coupling-box hereinbefore described. The fulcrum for the lever is the lower end of the chain 24 30 or other suitable connection, which chain is suitably connected to the under side of the skeleton segment 25, hereinafter more fully described. The lower end of the chain, it will be seen, is connected with the hand-lever 23 between the pivot and handle end thereof. The said lever 23, as will hereinafter appear, is of extensible form. When the attachment is connected to a plow and when the latter is being used as a riding-plow, the handle of the 35 lever will be within convenient reach of an operator occupying the seat 26, suitably clamped or otherwise fastened to the beam 12 above the plow-point. The said handle 23, it should be stated, is outwardly curved between its ends, so as to be in position to be reached by the right hand of the operator.

A rack-bar is shown at 27, (see, for example, Figs. 1, 3, and 9,) said rack-bar having teeth 40 on its right side coöperative with a knife-edge

28, united to the hand-lever 23, adjacent said rack-bar. The under side of the rack-bar has a hook or bend to receive the beam 12, while the upper end of said bar is extended forward and is suitably fastened to the coupling-box hereinbefore described. When it is desired to raise or lower the beam 12 and correspondingly operate the plow-point, the knife-edge 28 will be disengaged from the teeth of the rack-bar 27 and the handle end 45 of the hand-lever 23 will be depressed or elevated, as the case may be, to secure the object desired, and when the beam and consequently the plow-point are in the desired adjusted position the knife-edge will be moved inward 50 into engagement with the teeth of said rack-bar. This elevation of the point of the plow is for the purpose of regulating the depth of the furrows.

The segment 25, to which reference has 55 hereinbefore been made, is bolted or otherwise suitably fastened between its front and rear ends to the horizontal portion of the yoke-shaped frame 15, which horizontal portion, it will be evident, is situated above the corresponding portion of the arch 11 of the axle.

Upon the upper side of the segment 25 a lever 30 is mounted, said lever being oscillatory about a vertical axis and being represented as pivoted at its forward end to the 60 forward end of the skeleton segment 25. Near the curved edge of said segment is arranged a series of perforations 31 in arcuate order, the arc being struck from the center of motion of the hand-lever 30. The hand-lever 30 is also extensible. When the plow is used as a riding or sulky plow, the handle of said lever 30 will be within ready reach of an operator in the seat 26. The lever 30 has between its ends a longitudinal slot 32, through 65 which the upper end of the rod 33 extends, the shank of the rod passing through a transverse slot 34 in the skeleton segment 25 and being extended downward and tapped or otherwise connected with one of the sections—say the section 19—of the coupling-box. When, therefore, the hand-lever 30 is swung either to the right or left, the rod 33 will be tipped either to the right or to the left in order to correspondingly tip the coupling-box, 70 consisting of the sections 18 and 19, thereby similarly tipping the beam 12 and the plow-point, just as is done by an operator in using the plow as a walking-plow. Normally the hand-lever 30 is maintained in an adjusted position by the pin 30^a, depending therefrom and adapted to enter any one of the perforations 31. The pivot 30^b, which unites the hand-lever 30 to the segment 25, is a loose one, whereby said lever can be readily raised 75 to carry the pin 30^a out of a perforation 31 in order to swing the lever in either direction to effect the results hereinbefore described.

On the outsides of the box-sections 18 and 19 and extending along the opposite sides of 80

the slots 21 therein are flanges 36, which flanges engage the square sides of the central arched portion 11 of the axle in order to prevent lateral motion of said axle or the forward or backward movement of one wheel 13 with respect to the other. In other words, the inner faces of the two flanges 36 properly guide the axle no matter to what position the sections of the boxing may be raised or lowered.

It will be remembered that the hand-levers 23 and 30 have been described as being extensible, this being for the purpose of bringing their handles into position to be grasped by the operator when using the ordinary handles of the plow should the operator prefer to walk, which handles are represented by dotted lines in Figs. 1 and 2. As the extensible construction is the same in each case, we will describe but one of the levers in detail—say the lever 30. Said lever 30 is provided with an extensible portion 37, which fits between complementary lugs, as 38, on the body or shank of the lever 30. When the extensible portion 37 is in its advanced position, in order to bring the handle thereon into reach of the rider occupying the seat 26 said extensible portion will be situated between both pairs of lugs 38, at which time the set-screw 39 on said extensible portion will fit into a forward perforation on the body of the hand-lever 30. Should it be desired to extend the hand-lever, the set-screw will be removed from said forward perforation into which it is threaded, after which the extensible portion will be drawn rearward until the set-screw coincides with a rear perforation in said body of the hand-lever 30, after which the set-screw will be fitted into said rear perforation in order to hold the extensible portion in its rearward adjusted position.

A caster, as 45, of some ordinary construction and serving its usual purpose may be employed in connection with the attachment, said caster being connected in any desirable way with the beam 12.

By our plow attachment hereinbefore described we are enabled in an effective, simple, and novel way to run out old rows or beds and to make new beds, and therefore a brief description of the action of the attachment in this use will be set forth. It will be assumed that the old beds or rows upon a field are three feet apart. Initially, therefore, the wheels 13 are adjusted toward each other on the outer horizontal portions of the axle 10 until they are such distance apart, at which time they are held adjusted by the holding-collars 14. One wheel is then placed in one depression and the other wheel is placed in the next depression of the field, with the bed between the wheels. The attachment, sulky, or carriage is then drawn across the field in order to run the plow-point under the bed between such depressions. The attachment or

sulky is then returned across the field in two other depressions next those first entered by the wheels to run the plow-point under the bed between said second two depressions. This operation is then continued throughout the field, and it will be apparent that each alternate bed is not plowed during the preliminary action, during which the attachment served as what might be properly considered a single-row carriage. During such operation of the attachment the wheels occupied what are known as the "old middles" or the depressions between the beds. After the field is plowed in the manner indicated it will be apparent that the latter presents deep wide furrows made by the burster, said furrows being twice the distance apart as the rows or beds, and it will be obvious that there is a broad rough bed between each of these furrows. Now by moving the wheels outward upon the axle until they are separated six feet apart or twice the width of the rows we have a wide-gage carriage. When the wheels are thus adjusted, we place one wheel in one furrow and the other wheel in another furrow and run the attachment across the field and in doing so run the plow-point under those beds which were not originally burst. The second stage of the operation is then continued in like manner throughout the field.

95

What we claim is—

1. In a plow attachment, an axle, a coupling device adapted for connection with the plow-beam and slotted for the passage of said axle, the latter having wheels at opposite sides of the coupling device, means for raising and lowering said coupling device, and independent means for swinging the coupling device side-wise and to cause a rocking movement of the plow-beam about its longitudinal axis and independently of the frame of the attachment.

2. In a plow attachment, a wheeled axle, a coupling device for connection with the plow-beam, and also adapted for upward and downward movement and swinging movement independently of said axle and the frame of the attachment, slotted for the passage of said axle, and consisting of two sections, a coupling-bar between the sections of the coupling device, movably connected to the axle, means for raising and lowering the coupling device, and independent means for swinging the same.

3. In a plow attachment, a wheeled axle, a coupling device for the plow-beam, and also adapted for upward and downward movement and swinging movement independently of said axle and the frame of the attachment, slotted for the passage of said axle, a segment suitably connected with the axle, a hand-lever, means operated by the hand-lever for swinging said coupling device to cause the beam to rock about a longitudinal axis, and a suitably-mounted lever connected with the coupling device for raising and lowering the same.

4. In a plow attachment, a wheeled axle, a

coupling device for the beam, slotted for the passage of the axle, a segment connected with said axle, and slotted, a rod connected with the coupling device and extending through the slot in the segment, a lever loosely connected with said segment and having a slot to receive said rod, detent means carried by the lever, coöperative with the segment, a second lever connected with the coupling-box, and detent means coöperative with the second lever.

5. In a plow attachment, a wheeled axle, arched between its ends and having lateral adjustable wheels at its outer portions, to form single or double row gages for the carriage, a yoke-shaped frame connected with the arched portion of the axle, a coupling device for the plow-beam, slotted for the passage of said axle, a segment upon said frame, having a slot, a rod connected with the coupling device and extending through said slot, a rack connected with the coupling device, a hand-lever pivotally connected with said coupling device and adapted to coöperate with the teeth of said rack-bar, a chain depending from the segment and connected with the lever, and a lever loosely connected with the segment, having a slot to receive said rod and a pin, the segment having perforations to receive said pin substantially as and for the purposes specified.

6. In a plow attachment, a wheeled axle, a coupling device for connection with the plow-beam, slotted for the passage of the axle and consisting of two sections, a coupling-bar between the sections of the coupling device and movably connected with the axle, a suitably-mounted segment, a hand-lever associated with said segment, a rod united with the coupling device and arranged for operation by said hand-lever, thereby to rock the coupling device and to cause a rocking motion of the beam about its longitudinal axis, and a flexibly-mounted lever connected with the coupling device for raising and lowering the same.

7. In a plow attachment, a wheeled axle, a coupling device for connection with the plow-beam, slotted for the passage of said axle and

consisting of two sections, a flexibly-mounted lever for raising and lowering the coupling device, a suitably-mounted segment, a hand-lever associated with said segment, and means arranged for operation by the hand-lever and for swinging the coupling device to cause a rocking motion of the beam about its longitudinal axis.

8. In a plow attachment, a wheeled axle, a coupling device for connection with the plow-beam, slotted for the passage of said axle and consisting of two sections, a coupling-bar between the sections of the coupling device, movably connected to the axle, a suitably-mounted segment, a hand-lever associated with said segment, a rod connected with the coupling device and arranged for action by said hand-lever to swing the coupling device and cause a rocking movement of the beam about its longitudinal axis, and independent means for raising and lowering the coupling device.

9. In a plow attachment, a wheeled axle, a coupling device for connection with the plow-beam, slotted for the passage of said axle and consisting of two sections, a coupling-bar between the sections of the coupling device, movably connected to the axle, a suitably-mounted segment, a hand-lever associated with said segment, a rod connected with the coupling device and arranged for action by said hand-lever to swing the coupling device and cause a rocking movement of the beam about its longitudinal axis, a lever, a flexibly-fulcrumed member for said lever, the latter being connected with the coupling-bar for raising and lowering the same, and means for holding the second lever in its adjusted positions.

In testimony whereof we have hereunto set our hands in presence of two subscribing witnesses.
